(57) **CLAIM**

The ornamental design for a display system for seatback mounting, as shown and described.

DESCRIPTION

FIG. 1 is a front perspective view of a first embodiment of the display system for seatback mounting embodying the new design, shown mounted in a seatback for illustrative purposes only;

FIG. 2 is a front perspective view of the first embodiment of the display system for seatback mounting, shown separate from the seatback;

FIG. 3 is a front elevational view of the first embodiment;

FIG. 4 is a rear elevational view of the first embodiment;

FIG. 5 is a left side elevational view of the first embodiment;

FIG. 6 is a right side elevational view of the first embodiment;

FIG. 7 is a top plan view of the first embodiment;

FIG. 8 is a bottom plan view of the first embodiment;

FIG. 9 is a front perspective view of a second embodiment of the display system for seatback mounting embodying the new design, shown mounted in a seatback for illustrative purposes only;

FIG. 10 is a front perspective view of the second embodiment of the display system for seatback mounting, shown separate from the seatback;

FIG. 11 is a front elevational view of the second embodiment;

FIG. 12 is a rear elevational view of the second embodiment;

FIG. 13 is a left side elevational view of the second embodiment;

FIG. 14 is a right side elevational view of the second embodiment;

FIG. 15 is a top plan view of the second embodiment; and,

FIG. 16 is a bottom plan view of the second embodiment. Features drawn in broken lines are shown for illustrative purposes only, and form no part of the claimed design.

1 Claim, 6 Drawing Sheets
